UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

BUMPER.

Application filed February 20, 1928. Serial No. 255,605.

This invention relates to vehicle bumpers and more particularly to a pivotal construction for connecting the bars of a bumper and an object of the invention is to provide a pivoted connection which may be more conveniently and economically constructed and assembled. It is a further object to produce such a construction which, at the same time, will present a more attractive appearance. 5 A further object is to provide a plate at the point of connection of the bars, which plate will allow a pivotal action of the bars relative to each other and which will improve the appearance of the bumper. A further 10 object is to provide an ornamental plate which will cooperate with a pin in pivotally connecting the bars of the bumper.

Further and more or less limited objects will be apparent from the following description, from the drawings, and from the use of the articles covered by the appended claims.

In the drawings Fig. 1 is a plan view of a bumper embodying my invention; Fig. 2 is a front elevation of the bumper shown in Fig. 1; Fig. 3 is a detailed fractional front elevation of an end of the bumper shown in Fig. 1; Fig. 4 is a detailed fractional front elevation of the ends of the impact bars used in the bumper shown in Fig. 1; Fig. 5 is a 20 detailed fractional front elevation of the end of a bumper using a modified form of my invention; Fig. 6 is a detailed fractional plan view of an end of the bumper shown in Fig. 1 or of that shown in Fig. 5; Fig. 7 is a section taken on line 7—7 of Fig. 6; Fig. 8 is a section taken on line 8—8 of Fig. 6 representing the bumper shown in Fig. 1; Fig. 9 is a section taken on line 8—8 of Fig. 6 representing the bumper shown in Fig. 5; Fig. 10 is a fractional front elevation of the ends of the bars used in the bumper shown in Fig. 5; Fig. 11 is a section taken on a line corresponding to line 7—7 of Fig. 6, through a bumper employing a modification of my invention; Fig. 12 is a perspective view of the wedge used in the modification shown in Fig. 11.

In describing and claiming the invention the impact bars will be considered the front 50 of the bumper and the terms "front" and "rear" will be used in view of such assumption. It is not, however, intended to thereby

limit the application of my invention to any particular position relative to the bumper or to the vehicle.

55

Of the several reference characters, 1 and 2 denote the upper and lower impact bars, respectively, of a bumper of the general type shown in McGregor Patent No. 1,372,154, issued March 22, 1921, wherein a rear bar 3 60 is pivotally connected at its ends to the ends of the impact bars and is connected at its central portion to the central portion of the impact section by means of the clamp 4.

Each of the impact bars 1 and 2 has an 65 eye 5 at each end, and at each end of the rear bar 3 there is fastened an end connector 6 which is provided with a horizontally projecting portion 7, having an aperture therein, adapted to extend between the eyes of 70 the impact bars. A pin 8 passes through the aligned eyes 5, 5 and the aperture in the portion 7 of the end connector 6 to pivotally connect the impact and rear bars.

A mask plate 9 is clamped to the front surfaces of the impact bars at each end of the bumper. This plate is adapted to bear upon the front surfaces of the impact bars and has rearwardly extending flanges 10, 10 at the top and bottom adapted to extend over the 80 edges of the bars and to cover the eyes at the ends thereof. The impact bars are here shown as cut down at 11 a distance equal to the thickness of the flanges 10, 10 in order to provide a smooth line in the outline of the 85 bumper. Such shaping may be omitted or may be varied to suit the particular configuration desired.

The outer end of each mask plate 9 extends to a point 11^b (Fig. 6) beyond the end of the 90 impact bars and so provides a bearing surface which will prevent inward longitudinal movement of the mask plate on the impact bars. A lug 12 projects from the inner surface of the mask plate 9, extending between 95 the impact bars and providing a bearing surface which will prevent outward longitudinal movement of the plate. There is an aperture 13 through the plate 9 and a lug 14 may project from the rear surface of the plate on 100 each side of this aperture, such lugs may extend through between the impact bars and will then prevent the rotation of the rear clamp plate 15. A bolt 16 passing through the aper-

ture in the mask plate 9, through the rear plate 15 and between the impact bars 1 and 2 serves to draw the front and rear clamp plates together.

5 In the modified form of my invention shown in Figs. 5, 9 and 10, the impact bar 1^a is shown as cut down at 11^a to a greater extent and having an eye 5^a which is shorter. The mask plate 9^a is shaped at 18 to form a curve of the 10 desired shape at the end of the bumper and is adapted to bear upon the front surfaces of the impact bars. The flange 10^a extends rearwardly from the mask plate to cover the lower end of the eye at the end of the impact bar 2^a. 15 A substantially horizontal projection 17, extending from the inner surface of the mask plate, is adapted to cover the upper surface of the eye 5^a and bear thereupon. The bolt 16 passing through the front plate 9^a, the rear plate 15, and between the impact bars 1 and 2, 20 serves to draw these plates toward each other. It is apparent that both the top and the bottom of the mask plate 9^a could be curved if such a configuration were desired, suitable 25 projections, such as 17, being provided to prevent the downward movement of the pin 8^a.

The bars are assembled by placing the apertures in the end connectors on the rear bar in alignment with and between the upper and lower spaced impact bars. The pin is then inserted in the eyes and in the aperture in the 30 end connector and washers 19, of felt or other suitable material, may be placed at the ends of the pins to prevent movement or rattling 35 thereof. The mask plate is then applied and the bolt 16 is tightened to hold the mask plate in position. The projecting flanges 10, 10 or 10^a and 17 prevent the withdrawal of the pins from the eyes.

40 In the modification shown in Figs. 11 and 12 a wedge shaped block 20 having slanting faces 21 and an aperture 22, is used to more rigidly hold the bars 1 and 2 in proper spaced relation. The bolt 16 passes through the 45 aperture 22 and the pressure of the nut at the end of the bolt forces the bars 1 and 2 apart and against the upper and lower flanges of the plate 9, thereby reducing the tendency to rattle. The block 20 may be of a somewhat 50 different shape and may have vertically extending shoulders adapted to bear upon the rear surfaces of the bars 1 and 2 in their vertically spaced positions. It is apparent that this wedge shaped block could be used 55 in place of the plate 15 with either of the front plates shown.

It is apparent that my invention may be 60 applied to bumpers of different construction and to different portions of the bumper and it is also apparent that various modifications may be made in the details of construction without avoiding my invention in its broader scope. For instance, suitable equivalents may be substituted for the eyes at the 65 ends of the impact bars or the end connectors

at the ends of the support bars. In describing the above various embodiments of my invention it is not intended to thereby limit the scope of my invention to the particular construction shown and described.

70

Having thus described my invention, what I claim is:

1. In a vehicle bumper, the combination with an impact section and a support section, 75 of a pin adapted to connect the two sections, and a plate adapted to be clamped to one of said sections and to retain said pin.

2. In a vehicle bumper, the combination with two members adapted to be pivotally connected, of a pin adapted to pass through 80 apertures in said members, and a plate having projecting portions adapted to retain said pin.

3. In a vehicle bumper, the combination with two bars adapted to be pivotally connected, of a pin adapted to pass through apertures in said bars, and a plate adapted to be clamped to one of said bars and having projecting portions adapted to retain said pin.

4. A vehicle bumper comprising an impact 90 section having an eye at an end portion, an auxiliary bar having an eye at an end portion adapted to be aligned with the aforesaid eye, a pin positioned in said eyes, and a plate adapted to enclose said eyes and retain said 95 pin.

5. In a vehicle bumper, the combination with bars adapted to be connected, of means for connecting said bars comprising a pin 100 passing through apertures in said bars, and a plate adapted to be clamped to one of said bars and to extend across and retain said pin.

6. A vehicle bumper comprising an impact section having an eye at an end portion, an auxiliary section having an eye at an end 105 portion adapted to be aligned with the aforesaid eye, a pin positioned in said eyes, and a plate adapted to be clamped to one of said sections and having projecting portions extending to retain said pin.

7. In a vehicle bumper, the combination with an impact section and an auxiliary section, of means for pivotally connecting said sections comprising aligned eyes in each section, a pin adapted to pass through said 115 aligned eyes, and a plate adapted to be clamped to one of said sections, said plate having a portion shaped to project across an eye to retain said pin.

8. In a vehicle bumper, the combination with an impact section and an auxiliary section, of eyes at the end portions of said sections, pins passing through said eyes, plates adapted to be clamped to one of said sections, said plates having projecting portions adapted 125 to extend across said eyes and projecting portions adapted to prevent longitudinal movement on said impact bars.

9. In a vehicle bumper, the combination with an impact section and an auxiliary sec- 130

tion, of aligned apertures in the sections to be connected, a pin passing through said apertures, a plate adapted to be clamped to one of said sections, said plate having projecting portions adapted to cover said apertures and retain said pins, and having projecting portions adapted to prevent longitudinal movement of the plate on said section.

10. In a vehicle bumper having pivotally connected portions of reduced width, the combination with a pin adapted to fit within apertures in said connected portions, of a plate having a flange intermediate its edges adapted to prevent the withdrawal of said pin.

15. 11. In a vehicle bumper having pivotally connected members, the combination with a pin adapted to fit within apertures in said members, of a plate having a flange intermediate its edges adapted to prevent removal 20 of said pin.

12. A pivotal connection for the bars of a bumper comprising aligned eyes in said bars, a pin positioned in said eyes, and a plate adapted to cover said eyes and retain said 25 pin.

13. In a pivotal connection for bumper bars, the combination with apertures in said bars, of pins adapted to be positioned within said apertures, a plate having portions 30 adapted to extend over the edges of said bars and a plate having slanting surfaces adapted to bear upon adjacent corners of said bars, and means for drawing said plates toward each other.

35. 14. In a vehicle bumper, the combination with two members adapted to be pivotally connected, of a pin adapted to pass through apertures in said members, a plate having projecting portions adapted to retain said

pin, and a felt washer between the end of said 40 pin and said projecting portion.

15. The combination with a pair of spaced bars and a bar to be pivotally connected thereto, of a pin adapted to pass through apertures in said bars, a plate having a surface adapted 45 to bear upon the front surface of said spaced bars and having projecting surfaces adapted to retain said pins in said apertures, a second plate adapted to bear upon the rear surfaces of said bars, and clamping means for 50 drawing said plates toward each other.

16. The combination with a pair of spaced bars and a bar to be pivotally connected thereto, of a pin adapted to pass through apertures in said bars, a plate having a surface adapted 55 to bear upon the front surfaces of said spaced bars, having projecting surfaces adapted to retain said pins in said apertures and having projecting portions adapted to prevent longitudinal movement of said plate on said 60 bars, a second plate adapted to bear upon the rear surfaces of said spaced bars, and clamping means adapted to pass between said spaced bars for drawing said plates toward each other. 65

17. The combination with a bumper bar having its ends of reduced width and a second bar to be pivotally connected thereto, of a pin adapted to be positioned in aligned eyes in said bars, a plate having an edge in alignment 70 with the widened portion of said first mentioned bar and having projecting portions adapted to prevent removal of said pin from said apertures, and means for securing said plate to one of said bars. 75

In testimony whereof, I hereunto affix my signature.

HERBERT S. JANDUS.
